UNITED STATES PATENT OFFICE

KARL KIEFER, OF CINCINNATI, OHIO.

CLOSURE FOR CONTAINERS.

1,103,054.

Specification of Letters Patent.

Patented July 14, 1914.

Application filed January 9, 1911. Serial No. 601,600.

To all whom it may concern:

Be it known that I, KARL KIEFER, a citizen of the United States, residing at Cincinnati, in the county of Hamilton and State 5 of Ohio, have invented a new and useful Improvement in Closures for Containers, of which the following is a specification.

The object of my invention is to provide a closure for bottles, jars, and the like, that 10 will be of simple construction and convenient to apply.

My invention consists in the details of construction and arrangement hereinafter more fully described and claimed.

15 In the drawings: Figure 1 is a side elevation of the closure; Fig. 2 is a front elevation of the same; Fig. 3 is a plan view of the same; Fig. 4 is a plan view of the cap illustrating how the clip is applied thereto; Fig. 20 5 is a detailed side elevation of the cap; Fig. 6 is a detailed front elevation of the same; Fig. 7 is a perspective view of the closure illustrating how the cap with its clip is applied to the neck of the container.

25 The container is represented in the drawing by its neck A only. This container and its cap B may be of any of the usual materials, and this form of closure is especially desirable where fragile materials are used, 30 on account of the fact that breakage and chipping of the fragile edges of the neck and cap are avoided.

The neck A of the container has a swelling C forming a shoulder thereon, by means 35 of which a pair of wire clips D may engage with said neck. The cap or cover B of the container, as shown, has four recesses 2 into which the hooks 3 of the two wire clips D engage. Extending downward from these 40 hooks 3 are members 3', and these members are joined by a transverse member 3'', which extends under the shoulder or offset formed by the swelling of the neck A. This transverse member 3'' has a loop 4 midway 45 between the downwardly extending member 3', which loop extends out from under the shoulder where the transverse part is engaged thereunder, so that a suitable instrument may be inserted to pry the clip into 50 and out of its engaging position. As will be noted, this transverse member 3'' is arched upwardly so that it avoids contact with the edges of the shoulder, but makes a two-point bearing with the shoulder at the 55 sides of the loop 4. Likewise, the hooks 3 extend at a downward angle into the re-

cesses 2 in the cap B so that contact with the edges of the cap is avoided, with the advantages hereinbefore referred to.

The entire clip is resilient, and its springiness not only allows it to be easily applied and disengaged from the container, but allows it to compensate for slight variations in the dimensions of the container and cap, as is necessary in practice.

60 In order that the clip D may be conveniently mounted as a fixture on the cap B, this cap is provided with lugs E, one of these lugs being adjacent to each recess 2, and formed on the convex outside surface or 70 periphery of the cap. As herein shown, the formation of the clip D is such that the members 3' in each clip converge somewhat as they extend down to the transverse member 3''. This formation is preferred, since 75 it reduces the size of the clip somewhat without impairing its efficiency. The exact angle at which these members 3' extend downward is immaterial, but, for co-operating with the clips D, the lugs E have their 80 surfaces adjacent to the members 3' of the clip inclined away from the members downwardly to such a degree as to allow a limited swinging movement of the clip outwardly from the container, the clip pivoting with 85 its hooks 3 in the recesses 2.

Relatively to the clip, the lateral extension of the lugs E is only such that the clip will be prevented from being disengaged 90 horizontally from the cap under the ordinary pressure exerted in applying the cap to the neck, but, as will be understood and as is clearly shown in Fig. 4, the clip may have its members 3' spread apart so that they slide over the sides of the lugs E when 95 applying the clip to the cap, as allowed by the elasticity of the clip. The inclination of the adjacent part of the lug E to the member 3' of the clip, as before stated, allows a limited movement of the clip, but this 100 movement, preferably, is not enough to allow the clips to slip over the swelling on the neck of the container without springing apart somewhat, so they hug the swelling C of the neck A closely when being pressed 105 down onto the container, and are prevented from rising with respect to the cap and displacing their hooks 3 from the recesses 2. While the lugs E thus limit the swinging of the clips away from each other, the adjacent 110 bulging of the convex surface of the periphery of the cap adjacent each member 3'

of the clip limit the swinging of the clips toward each other, so that they are held practically in position for ready application of the cap, with the clips, to the neck of the container. With this provision, the engagement of the transverse part 3" of the clip may be automatically effected, if pressure is applied to the cap B, so as to compress the gasket G, between the cap and neck, enough to bring said transverse part 3" down so low that the hugging pressure of the clip overcomes the resistance at the shoulder.

The convenience of such an arrangement for rapid closing of the containers, such as bottles and jars, is apparent, and it will also be seen that the cap with its lugs for the purpose described, is of very simple formation and not difficult to produce, which is an essential requirement in such an article.

Having fully described my invention, what I claim as new and desire to secure by Letters Patent is:

In a closure for containers, a neck, and a

cap having a convex outer surface or periphery, and a substantially flat upper surface with upwardly open recesses therein adjacent to the periphery, and a clip having hooks engaging in the upwardly open recesses and having members extending down and embracing a segmental part of the cap, and lugs on the cap having surfaces adjacent to the downwardly extending members of the clip that are inclined away from said members from said recesses downward, so that the members have a limited swinging movement, with their hooks acting pivotally in said recesses.

In testimony whereof I have signed my name to this application in the presence of two subscribing witnesses, this 3rd day of January, 1911.

KARL KIEFER.
